UNITED STATES PATENT OFFICE.

ISAAC ADELBERG AND MAX J. SINDLER, OF BALTIMORE, MARYLAND.

COLLAR.

1,204,726.

Specification of Letters Patent. Patented Nov. 14, 1916.

Application filed July 31, 1914. Serial No. 854,425.

To all whom it may concern:

Be it known that we, ISAAC ADELBERG and MAX J. SINDLER, citizens of the United States, residing at Baltimore city, State of Maryland, have invented certain new and useful Improvements in Collars, of which the following is a specification.

This invention relates to that class of collars known as high turn-down collars and has for its object to provide a collar of this class which will be entirely free from closed buttonholes.

The difficulty in securing a collar of this character upon the neckband of a shirt where closed buttonholes are used is well known and many attempts have been made to overcome this difficulty, in some of which attempts a portion of the closed buttonholes usually used are dispensed with and the principal object of our invention is to entirely dispense with passing closed buttonholes in stiff, starched collars, over buttons and studs as has universally been the custom.

With this special object in view our invention consists in the improved construction and arrangement of the parts comprised in a collar of this class which will be hereinafter fully described and afterward specifically claimed.

In order that the construction and operation thereof may be readily comprehended we have illustrated approved embodiments of our invention in the accompanying drawings and we will now proceed to specifically describe the invention in connection with the said drawings, in which—

Figure 1 represents a perspective view of our improved collar looking at the rear side thereof and showing inside of the front portion. Fig. 2 represents in elevation the inside of the collar shown in Fig. 1, on a smaller scale, the collar being stretched out, Fig. 3 represents in perspective, a modified construction of collar embodying our invention, showing, as in Fig. 1, the outside of the rear and the inside of the front of the collar, and Fig. 4 illustrates in elevation on a smaller scale the inside of the collar shown in Fig. 3, the collar being stretched out straight.

Like reference characters mark the same parts wherever they occur in a plurality of the figures of the drawings.

Referring specifically to the drawings 5 indicates the outer fold and 6 the inner fold

of a collar of the character specified, the material of the collar being of any approved type but usually of such textile fabric as linen.

In constructing our collar as shown in the drawings we have dispensed with the buttonhole at the rear in the inner fold 6 and have provided a tongue 7 secured along its lower edge 8 to the lower edge of the inner fold 6 and free on its sides and upper edge, in order that it may be slipped under the neck band of the shirt (not shown), or into a pocket in the neck band to be provided for the purpose.

Referring specifically to Figs. 1 and 2, one end 9 of the inner fold 6 is provided with a substantially hooked end 10 between which and the end of said inner fold is a slit or passage 11 which curves into said hooked end 10 and terminates in an almost complete circular opening 12. Inclined downward and outward, near the end 9 of the inner fold 6, we provide a slit 13 the purpose of which will be hereinafter described. 70 The opposite end 14 of the inner fold of the collar is extended somewhat beyond the end 15 of the outer fold 5, the extension being of substantially triangular shape with its end provided with a hook like end 16 formed 75 by cutting away a portion of the fold at 17, the upper side of the hook 14 being substantially in line with the upper edge 18 of the collar when folded.

When it is desired to adjust the collar as 90 hereinbefore described and shown in Figs. 1 and 2 upon the neckband of a shirt the tab or tongue 7 is engaged in the neckband in the manner described, the shank of the button or stud in the neckband slipped 95 through the passage 11 into the circular opening 12, and the end 14 of the inner fold 6 slipped through the slit 13 with its hooked end 16 contacting with the inner fold above the said slit 13, as shown in 100 Fig. 1.

From the foregoing it will be obvious that the collar will be firmly held in position without any tendency to rise or fall and the trouble of working the closed buttonholes 105 of stiff, starched material over studs or buttons is entirely obviated.

The collar shown in Figs. 3 and 4 comprises an outer fold 5^a and an inner fold 6^a the main bodies of which are of the same 110 construction as that of the collar shown in Figs. 1 and 2, but the ends of the inner fold

are somewhat differently constructed. The tab 7^a secured along its inner edge to the lower edge of the inner fold 6^a is of the same construction and operable in the same manner as illustrated in Figs. 1 and 2 and hereinbefore described. The ends of the fold 6^a of the construction shown in Figs. 3 and 4 are constructed to operate in substantially the same manner as those above described but are of a different formation, the end 10^a ending slightly inside of the end of the outer fold 5^a but being provided with a passage 11^a leading into a substantially circular opening 12^a to receive the shank of the button or stud and the upper portion of that end of the fold 6^a being rounded and extended beyond the end of the outer fold. The end 14^a of the inner fold 6^a is hooked shaped as at 16^a, the hook extending downward instead of upward as in the case of Figs. 1 and 2. In adjusting this form of collar the shank of the button or stud is passed through the channel 11^a and seated in the substantially circular opening 12^a after which the end 14^a is slipped into the slit 13^a and the hook end 16^a engaged over the bottom end of the slit securely holding the parts in the position shown in Fig. 3.

It will be observed, that one of the terminals of the slits 13, 13^a, forms the engaging edge of the respective hook, in the slit 13 the upper terminal and in slit 13^a the lower terminal, and these slits are inclined from these hook engaging terminals toward the adjacent end of the collar. This particular arrangement of each slit, allows a large portion of its slit engaging hook to pass

through the slit and lie against the inner face of the inner fold, thereby forming an 40 effectual lock for the ends of the collar and avoiding an obstruction to the tie when drawn between the folds.

From the foregoing it will be observed that we have entirely dispensed with closed 45 buttonholes in our improved collar and while we have particularly described the construction and location of the various parts, it will be obvious that changes may be made therein within the scope of the 50 appended claim, without departing from the spirit and scope of the present invention.

Having thus fully described our invention what we claim as new and desire to secure by Letters Patent of the United 55 States is:

A collar comprising an inner and outer fold, said inner fold being provided with an integral hook-like attaching means at each end thereof and which are formed by 60 shaping the extremities of the fold so that they will lie in alinement with said fold, and a slit formed in one end of the fold for engaging with the hook-like means on the other end, the other hook-like means 65 being formed and located to engage a collar button in the shirt for attaching the front of the collar to the shirt.

In testimony whereof we affix our signatures in presence of two witnesses.

ISAAC ADELBERG.
MAX J. SINDLER.
